UNITED STATES PATENT OFFICE

2,525,459

ADAPTER FOR PLASTIC DOOR HANDLES

John W. Pulaski, Erie, Pa., assignor to General
Electric Company, a corporation of New York

Application October 17, 1949, Serial No. 121,682

3 Claims. (Cl. 292—348)

1

This invention relates to door handles and more particularly to a device that makes possible the utilization of a molded plastic handle for a refrigerator door.

It is an object of this invention to provide a device that will materially aid in satisfactory operation of a plastic handle for a refrigerator door.

It is a further object of this invention to provide a device that will give a long, useful life to a molded plastic handle for a door.

Broadly, this invention comprises a device that is interpositioned between a plastic handle and a latch releasing device on a refrigerator door. Through the utilization of this invention, a plastic handle can be made to release a latch which holds the door of a refrigerator closed.

Further objects and advantages of this invention will become apparent and the invention will be better understood from the following description referring to the accompanying drawing and the features of novelty which characterize this invention will be pointed out with particularity in the claims annexed to and forming a part of this specification.

In the drawing, Fig. 1 is a plan view, partly in section, showing a plastic handle attached by means of the present invention to a refrigerator door; Fig. 2 is a plan view, partly in section, of a plastic handle attached to the adapter itself; Fig. 3 is an end view of a plastic handle attached to the adapter; while Fig. 4 is the perspective view of a plastic handle ready for assembly with the adapter.

Referring to the drawing, a refrigerator 1 is provided with a door 2 having a conventional latch operating pin 3 for releasing the door from the refrigerator body, permitting the door to swing about hinges (not shown) giving access to a storage space within the refrigerator body.

A mounting plate 4 has a base 5 which matches the contour of door 2 and is positioned on the door adjacent the latch operating pin 3 by suitable bolts 6a passing through openings 6 into the door 2. Latch operating pin 3 extends through an opening 7 in base 5. In addition to the base portion 5, two lateral flange members 8 are provided in spaced relationship on plate 4 and they are in planes at right angles to base portion 5. Within each flange member 8, an opening 9 is provided which is a bearing for a pivot pin 10. The handle mechanism pivots about pivot pin 10 and operates the latch operating pin 3.

An adapting member or adapter 11 is located between the flanges 8 of base member 4. The

2

adapter comprises a bottom portion 12, two side portions 13 and an end portion 14.

Side portions 13 of the adapter are in parallel planes perpendicular to the bottom portion 12. End portion 14 is in a plane substantially at right angles to and is welded or otherwise connected to side portions 13. Each side portion 13 has an opening 15 therein through which pivot pin 10 passes. The openings 15 in the side portions 13 are so formed that an inner shoulder 16 is positioned on the adjacent faces of each side portion 13. Shoulders 16, in turn, serve as a bearing surface for a coil spring. In addition to openings 15, each side portion 13 contains one of a pair of aligned openings 17 and 18. Opening 17 is threaded to operatively engage the threaded portion of a screw 19 while opening 18 is cut large enough to allow all but the head of screw 19 to pass therethrough.

In the adapter 11, a lip 20 is provided on each of the side portions 13. Each lip comprises an inturned portion which is substantially perpendicular to its respective side portion 13 and end plate or portion 14, but the lips 20 are not parallel to the bottom portion 12.

A solid plastic handle 22a is provided for operating the pin 3. The handle may be made of any suitable plastic material, such as polystyrene or methyl methacrylate. The handle has a base portion 22 and an extended or gripping portion 23 of any conventional design. Base portion 22 is provided at each side with a groove 24, and these grooves are operatively engaged by lips 20 of adapter 11. Below grooves 24, the sides 24a of base portion 22 are cut away to an extent that the thickness of the body portion below the grooves, plus the thickness of the sides 13 of the adapter 11, is substantially equal to the thickness of the section of base 22 above the grooves 24. The base portion 22 is also provided with a portion 26 which extends below groove 24 to give a greater shear area in the handle. The extended portion 26 has a bottom 25 shaped to match the bottom portion 12 of adapter 11. The handle 22a is also provided with a rounded portion 28 which matches a rounded portion 29 on the side portion 13 of the adapter.

When handle 22a is fitted into adapter 11, lips 20 are slid into the grooves 24 until back portion 30 of base 22 contacts the end portion 14 of adapter 11. Bottom portion 25 of base portion 22 is then against bottom portion 12 of adapter 11 and rounded portion 28 fits against rounded portion 26 in handle 22a. Screw 19 is then inserted through opening 18 in one of the side members

13 and threaded into the corresponding threaded opening 17 in the other side 13. When the screw is tightened, the side portions 13 are pressed against the base portion 22 of the handle, and lips 20 on the adapter engage grooves 24 on the plastic handle. Consequently, when handle 22a is pulled to open the door, the opening force is distributed the entire length of lips 20. With the structure of this invention, handle 22a cannot slip out of engagement with flange portion 20 unless side members 26 below groove 24 are sheared away from base portion 22 of plastic handle 22a.

A striking plate 31 is positioned between the plastic handle and operating pin 3. The striking plate comprises an elongated portion which extends from the forward point 32 of the plastic handle to pivot pin 10. At pivot 10, the striking plate is shaped to form a loop 34 through which pivot pin 10 extends to support the striking plate. Striking plate 31 has a protrusion 33 which engages a pin 3 when extended portion 23 of the handle is pulled away from the refrigerator door. The loop 34, which fits around pivot pin 10, is of a convenient width that easily fits between side portions 13 of adapter 11.

A spring 21 is provided for keeping bottom portion 12 of adapter 11 against base 5 of mounting plate 4. Spring 21 is made of conventional wire material and is first formed in a U-shape with two legs 35 and 36 joined by a cross member 37. Legs 35 and 36 of the spring 21 are each bent through several turns so as to form loops 38 which fit over shoulders 16 of openings 15 in adapter 11. Pivot pin 10 passes through loops 38 of spring 21. Cross member 37 passes between striking plate 31 and support plate 4 and serves to keep the striking plate resiliently against plastic handle 22a. The free ends of the legs 35 and 36 of the spring 21 rest up against base portion 5 of mounting plate 4 and aid in the resilient spring keeping the handle member in a retracted position with bottom portion 12 of adapter 11 against base 5 of mounting plate 4.

The component parts of the handle are assembled in the following manner. Adapter 11 is slid over base portion 22 of handle 22a with lips 20 on side portions 13 sliding into grooves 24 on base portion 22. Spring 21 is then inserted over shoulders 16 adjacent openings 15 with the free ends 35, 36 located away from base portion 22 of handle 22a. Striking plate 31 is then slid under the cross member 37 of the spring and placed in position for loop member 34 to be engaged by pivot pin 10. Screw 19 is then inserted through opening 18 in one side 13 into threaded engagement with the threaded portion of hole 17 in the other side 13 and tightened to firmly position the plastic handle. The assembly, including the handle, adapter 11, spring 21, and striking plate 31, is then positioned in operative engagement with the mounting plate 4. Pin 10 is inserted through openings 9 in mounting plate 4, openings 15 in adapter 11, loops 38 in spring member 21 and loop 34 of striking plate 31. The pin end is then peened to retain the component parts in operative positions.

It is to be noted that in the operative association between handle member 22a and adapter plate 11 there is an adjustment in the positioning of the two parts. Since there is a sliding engagement between the adapter plate 11 and the grooves 24 of the handle 22a, there can be an adjustment in position until screw 19 is securely

fastened. After screw 19 has been fastened, however, then there is no movement between the handle and adapter plate 11.

Modifications of this invention will occur to those skilled in the art, and it is to be understood, therefore, that this invention is not to be limited to the particular arrangement disclosed, but that the appended claims are meant to cover all the modifications which do not depart from the spirit and scope of this invention.

What I claim as new and desire to secure by Letters Patent of the United States is:

1. A latch operating device for a refrigerator door comprising a latch operating pin, a mounting plate having a base conforming with the surface of the door and having an opening to provide for the extension of said pin therethrough, said mounting plate including a pair of flange members extending in parallel planes perpendicularly from the plane of said base, a pivot pin mounted on said flange members, an adapter mounted within said flange members, said adapter having a bottom portion, two side portions, and an end portion, said side portions being in parallel planes perpendicular to said bottom portion, said adapter being pivotally mounted on said pivot pin, each of said side portions including a turned-in lip, said lips being directed toward each other, said end portion of said adapter being substantially perpendicular to the planes of said side portions and being rigidly secured thereto, a molded plastic handle operatively engaged by said adapter and pivotable with said adapter about said pivot pin to actuate said latch operating pin, said handle having a base portion and a gripping portion, a pair of grooves in said base portion, said lips extending into said grooves, means engaging said side portions of said adapter for forcing said side portions toward each other to maintain said adapter in engagement with said base portion of said handle, said base portion of said handle being recessed below said grooves to a depth substantially equal to the thickness of said side portions of said adapter and including an extended portion below said grooves in said base portion that conforms with the inner surface of said adapter.

2. An adapter for a plastic handle, said adapter comprising a bottom portion, two side portions, and an end portion, said side portions being in parallel planes extending perpendicularly from the plane of said bottom portion, each of said side portions including a bearing surface for a pivot pin, said side portions being provided with a pair of aligned openings, one in each of said side portions, each of said side portions including a lip extending inwardly therefrom, said end portion extending from said base portion substantially perpendicular to and rigidly secured to said side portions, and a screw extending through said aligned openings and adapted to engage said side portions to move said side portions toward each other.

3. The combination of a plastic handle and an adapter therefor, said combination comprising a molded plastic handle having a base portion and a gripping portion, said handle base portion having a pair of grooves therein, said base portion including an extended portion below said grooves in said base portion to increase the shear area of said base portion, said adapter having a bottom portion and two side portions and an end portion, said side portions being in parallel planes perpendicular to said bottom portion and extending therefrom, a pivot pin, each of said side por-

tions including a bearing surface for said pivot pin, said side portions having aligned openings therein, each of said side portions including a lip extending inwardly from its respective side portion, said lips being received within said grooves in said handle base portion, and threaded securing means for forcing said side portions of said adapter toward each other to maintain said adapter in engagement with said handle.
